CRAYON HOLDER

Frank G. Prain, Spokane, Wash.

Application November 14, 1938, Serial No. 240,247

2 Claims. (Cl. 120—13)

The object of this invention is to provide an improved holding device for crayons.

A particular object is to provide a device of this character which is especially adapted for use by lumber scalers whereby a lumber crayon, which is usually of large size, may be secured in one end of the device and a relatively small pencil may be secured in the other end, thus enabling the scaler to mark logs with the lumber crayon and insert recordings in his book with the pencil.

A feature of the invention resides in an improved means for holding the large crayon whereby the same may be used up to a very short length and still be efficiently secured in the device.

15 A further feature resides in a holding device comprising a hollow holding member having means at one end thereof for releasably and adjustably holding a large crayon, and the remaining end having means for releasably and adjustably holding a relatively small pencil.

20 A very special feature of the invention resides in a holder of cylindrical form having crayon gripping fingers for gripping the large crayon in such a manner as to engage the flat faces with 25 which these polygonal crayons are provided, the engagement being effective irrespective of the fact that the crayon is of polygonal cross section and the holder and fingers are of cylindrical and convex form, respectively.

30 The invention has many other features and objects which will be more fully described in connection with the accompanying drawing and which will be more particularly pointed out in and by the appended claims.

35 In the drawing:

Fig. 1 is a view in side elevation showing the device of my invention in the form of a lumber scaler's marker.

40 Fig. 2 is a sectional view on line 2—2 of Fig. 1, with the parts shown on an enlarged scale, and illustrating the crayon in a fixed adjustment.

Fig. 3 is a view similar to Fig. 2, showing the crayon released so that it may be adjusted or removed.

45 Fig. 4 is a cross sectional view on line 4—4 of Fig. 2.

Fig. 5 is a view in elevation of the holder showing the gripping fingers in elevation.

50 Fig. 6 is an enlarged fragmentary view illustrating the manner in which the fingers grip the flat faces of the crayon.

Fig. 7 is a sectional view on line 7—7 of Fig. 1, with the parts being shown on an enlarged scale.

55 Fig. 8 is a view in elevation of the pencil gripping sleeve detached from the holding device.

Like characters of reference designate similar parts throughout the different figures of the drawing.

As shown, the device includes a hollow holder of cylindrical form, as indicated at 1. This holder is formed of spring brass or other resilient metal and has means at one end for holding a relatively small lead pencil 2, and the remaining end is provided with means for holding a relatively large crayon 3.

10 Reference will first be made to the novel crayon holding means.

The crayon shown, is what is termed "lumber crayon" partly because it is used by scalers and must be of relatively large size in order to effectively perform its function in the use of marking logs and lumber. To the best of my knowledge, this lumber crayon is always formed with a polygonal cross section, which, specifically, is hexagonal, having six flat faces 4, and six corner portions 5, extending longitudinally thereof. A further characteristic is that lumber crayon comes in a single stock size, as far as I know, and its greatest cross-sectional dimension is through opposed corner portions, as will now be clear. It is 20 a feature of this invention to make the holding device for this special purpose as cheaply as possible, which is preferably in the form of cylindrical tubing, and adapting the same to the special requirements necessitated by the diameter and shape of the crayon which the holder is designed to accommodate.

Thus, I select a tubing, preferably though not essentially of resilient or spring metal, and which has an internal diameter such as will permit the 35 crayon 3 of being easily telescoped into the holder 1, with a very slight clearance necessitated by slight variations of size of the stock crayons.

By reason of this proportion, I am able to provide crayon gripping fingers in a very accessible 40 position for gripping the crayon. At the crayon end of the holder, I split the latter to form a plurality of gripping fingers 6, equal in number to the number of flat faces 4, on the crayon 3. By reference to Fig. 5, it will be seen that the end of the holder is sub-divided longitudinally in the form of slots 7, which are wide enough to span the corner portions 5, and whereby the resulting fingers will be sufficiently narrower than the width of the flat faces 4, so as to engage the latter with the lateral edges of the fingers, as shown in Figs. 4 and 6. Thus, each finger 6, will have two edge portions 8, engaging each flat face 4, longitudinally of the latter. This is important because the fingers 6, being formed from the cylindrical 50

holder 1, are convex transversely of their length, and it is a feature to provide an effective engagement with the crayon without going to the expense of changing these convex fingers into flat fingers. Further, it will be clear that the slots forming the fingers 6, serve to receive the corner portions of the crayon so that the latter will always be inserted with the corner portions 5 in registry with the slots 7, thereby insuring a proper 5 positioning of the fingers 6 with respect to the flat faces of the crayon. Thus it will now be clear how I avoid the necessity of an inner crayon holding sleeve inside holder 1, thereby making the latter at once a holder for the device, and a 10 receiver for the crayon.

The outer ends of fingers 6, are provided with peripherally disposed releasing grooves 9, extending transversely across the fingers and collectively forming an annular channel.

20 Reference will next be made to the means for causing contraction and permitting expansion of the gripping fingers.

A ferrule 10, is slidably mounted on holder 1, and may be provided with a knurled area 11, to 25 facilitate gripping the ferrule to shift the same. At its outer end, the ferrule is provided with a contracting portion which may be in the form of a shoulder 12 of annular form and projecting inwardly from the bore of the ferrule. It will be 30 noted that the grooves 9, in the fingers, are sufficiently inside the terminal ends thereof to form shoulders 13, which serve to prevent the ferrule from being completely shifted off from the handle 1 unless an excessive thrust is applied, thus 35 guarding against loss of the ferrule. When the ferrule is shifted into the releasing position shown in Fig. 3, with the shoulder 12 arrested by shoulders 13, and registering with grooves 9, the fingers 6 will be permitted to expand or spring 40 radially outwardly a slight extent. This permits of longitudinal adjustment of the crayon 3, or insertion of a new crayon. When the ferrule is shifted inwardly to the Fig. 2, position, the contracting shoulder will ride up out of groove 9, onto 45 the outer faces of fingers 6, thereby contracting the latter into firm engagement with the crayon.

Reference will next be made to the means for adjustably holding a relatively small size lead pencil.

50 The holder or handle 1, is suitably provided with a reduced end 14, provided with a bore 15, which may be cylindrical, and which is greatly reduced in diameter with respect to the main bore of the holder, which may be indicated at A. A 55 pencil holding sleeve is shown at 16, which may have a knurled cylindrical end 17, to facilitate manipulation thereof. The bore of sleeve 16, is preferably cylindrical but I advisedly taper the exterior from the enlarged knurled end 17, to the 60 other extreme end 18. To insure a pencil gripping action, I split the sleeve 16, preferably although not essentially, throughout its length. As it is never necessary completely to withdraw 65 said sleeve from the holder, and to avoid loss of the sleeve, I preferably turn up a portion of end 18, to form a shoulder adapted to engage the shoulder 20, to prevent complete withdrawal of the sleeve.

70 While the use and operation may be clear from

the foregoing description, I will briefly recapitulate the same as follows:

With the device equipped as shown in Fig. 1, a 5 scaler, with the use of one hand, can employ the large crayon to mark a log or other article, and then switch the device and use the pencil 2, to record his marking in a record book or sheet. Thus, in one device, the scaler has the means for both marking and entering an entry.

If crayon 3, wears down, the ferrule can be 10 shifted to the Fig. 3, position, to permit adjustment, and then back to the Fig. 2, position to fix the adjustment. In this connection it is important to note that the gripping action on crayon 3, is almost wholly near and at the end of the 15 holder, hence, even if the crayon is as short as indicated by dotted line B, in Fig. 2, it can be firmly gripped and used as long as there is sufficient length left to extend from the gripping area to a point beyond the end of the holder. This 20 affords a very material saving in the cost of crayons.

When adjustment of pencil 2, is necessary, the knurled end 17 can be gripped with the fingers and twisted outwardly thereby releasing the 25 grip of sleeve 16 on the pencil and permitting a greater or less projection thereof or insertion of a new pencil, with only a slight outward movement of the sleeve.

It is believed that the device of my invention 30 will be clearly understood from the foregoing description, and while I have herein shown and described one specific form of the invention, I do not wish to be limited thereto except for such limitations as the claims may import.

35 I claim:

1. In a holding device for large size crayons, a holder having a plurality of resilient gripping fingers for peripheral engagement with the crayon and said fingers having releasing recesses 40 peripherally disposed thereon near the ends of said fingers, and a ferrule movable on said fingers and having a contracting portion adapted to register with said recesses when said ferrule is shifted outwardly toward the ends of said fingers 45 to permit expansion of the latter and said contracting portion engaging said fingers to contract the latter against the crayon when said ferrule is shifted inwardly along said fingers.

2. In a holder for large size crayons of polyg- 50 onal cross section having a plurality of longitudinally disposed flat faces and corner portions, a cylindrical handle sleeve having an internal diameter slightly in excess of the maximum cross sectional dimension of the crayon and provided 55 with a holding end longitudinally split into a plurality of concave resilient gripping fingers laterally spaced sufficiently to be permanently separated from each other and the spacing being sufficient to cause said fingers to laterally span 60 the corner portions of the crayon with edge portions of the fingers extending along the flat faces of the crayon and the concave portions between said edge portions being in spaced relation from said flat faces of the crayon, and means for contracting said fingers to engage said longitudinal edges portions thereof against the flat faces of the crayon with the corner portions of the latter projecting radially between said edge portions.

FRANK G. PRAIN. 70
